UNITED STATES PATENT OFFICE.

ROGER H. CLAPP, OF PHILADELPHIA, PENNSYLVANIA, ASSIGNOR TO CLAUDE A. WITTER, OF PHILADELPHIA, PENNSYLVANIA.

RAILWAY RAIL.

Application filed July 11, 1924. Serial No. 725,339.

To all whom it may concern:

Be it known that I, ROGER H. CLAPP, a citizen of the United States, residing at Philadelphia, in the county of Philadelphia and State of Pennsylvania, have invented certain new and useful Improvements in Railway Rails, of which the following is a specification.

This invention relates to railway rails and is especially useful in connection with rails for steam railroads.

One of the objects of my invention is the provision of a two-part rail, one part of which,—the base,—is practically a permanent member, and the other part of which,—the head,—is renewable.

The primary purpose of this construction is the reduction of the cost of maintenance over the present style of rails used. In the present rail, only about one-third of the head, or about 14% of the entire weight, is ever used up in regular service, the remaining 86% being used for "relying" or scrap.

I am aware that many attempts have been made to provide a two-part rail but, in so far as I am aware, none of them have met with commercial employment for the reason that their structural characteristics were such as to introduce difficulties or objections which outweighed the advantages to be gained. Certain of the difficulties of this character will become manifest in connection with the description of my invention.

I propose to provide a two-part rail of a practical character such as will enable its use in the realization of the advantages incident to such a general construction.

Another object of the invention is to provide an improved two-part rail in which the head member is reversible as well as renewable.

Still another object of the invention is to provide a two-part rail in which provision is made for contraction and expansion.

More specifically it is an object of my invention to provide a two-part rail, the parts of which may be simply manufactured.

How the foregoing, together with such other objects as may hereinafter appear, or are incident to my invention, are obtained is illustrated in the accompanying drawing in which the figure is a partially

sectional and partly isometric perspective view of a rail embodying my invention.

Referring now to the drawing, the reference character A designates the base rail which is of a construction such that it may be readily rolled. This base rail member can well be made of soft structural steel and is more or less permanent. It may well be attached to the ties by screws, the reason why spikes are at present employed being that the rail, as a whole, must be readily removable.

The base rail has a groove 7 located in its upper face and extending longitudinally thereof, such groove being central of the rail. This groove is formed by the small flange 8 and the upstanding flange, knee or column 9. In other respects, the base rail may be of the usual section.

The head rail member B is of T section, comprising the usual head 10 and a depending flange 11 which is located centrally of the head and extends longitudinally of the rail member. The head rail may be readily rolled.

The depending flange 11 fits within the groove 7 and abuts against the upstanding flange 9 or column of the base rail.

The two flanges are provided with bolt holes through which the bolts 12 pass and in which they have a loose fit so that substantially the only function performed by such bolts is to secure the flanges together, all of the weight being transmitted directly to the base rail member. The rail is preferably assembled with the column 9 on the outside so that this column receives the lateral thrusts, the toe of the flange 11 being held in the groove.

The head rail, being of T construction, is capable of being reversed as wear takes place, to which end I so locate the bolt holes in the respective members that they are equidistant from the ends of the rails. In order to further take care of expansion and contraction, the bolt holes may be elongated as indicated.

Since the bolts are subject to no shearing stresses, it will be apparent that the number thereof need not be great.

While the weight of the rail may be somewhat in excess of the standard rail nevertheless the reversible feature, not to mention the renewable feature, will far more than

- compensate for such increased cost. In the neighborhood of 30% of the rail can be used up before removal of the head rail member. Furthermore, the amount of metal and also the disposition of the metal, particularly in the base rail member, are such that the rail, considered as an entirety, is considerably more rigid than the present rail, which is an item of great importance and advantage for the reason that, owing to the rapid development of locomotive power, the increased tonnage, and also the increase in train speeds, the present rail has been found to be too elastic.
- 15 It will be noted that the column 9 terminates short of the head i. e., there is no load transmitted by the head to such column. If there were any load transmitted by the head to the column, the head would pound out and elongate laterally.
- 20 Among other advantages are that forms of splices now in use may be employed with this rail; bonding for electric signals is more effective; there is less concentration of expansion and contraction; there is less localization of deflection under load; the dangers incident to breakage are minimized; and the head and base rails may be staggered. On curves, while the head rail may not be reversed, nevertheless it can be reversed which is of great advantage as the wear is excessive.
- 25 I claim:
- 30 1. A railway rail comprising a base rail member having a groove and an upstanding flange, a head rail member having a head and a depending flange the lower edge of which fits the groove and rests upon the base rail for the transmission of the load,

the upstanding flange being out of contact with the head, bolt holes in the flanges disposed so the head rail member may be reversed, and bolts for securing the flanges.

2. A railway rail comprising a base rail member having a groove and an upstanding flange, a head rail member having a head and a depending flange the lower edge of which fits the groove and rests upon the base rail for the transmission of the load, the upstanding flange being out of contact with the head, bolt holes in the flanges disposed so the head rail member may be reversed, and bolts for securing the flanges certain of the holes being elongated to provide for expansion and contraction.

3. A railway rail comprising a base rail member having a groove and an upstanding flange, a head rail member having a head and a depending flange the lower edge of which fits the groove and rests upon the base rail for the transmission of the load, the upstanding flange being out of contact with the head, bolt holes in the flanges disposed so the head rail member may be reversed, and bolts for securing the flanges, the bolts having a loose fit for expansion.

4. A railway rail comprising a base rail member having a central groove and an upstanding flange to one side of the groove, a head member having a central depending flange adapted to fit in said groove and to transmit all of the weight to the base rail, and means for securing the flanges together.

In testimony whereof, I have hereunto signed my name.

ROGER H. CLAPP.
